FIRE ALARM

Edward Sarcione, North Andover, Mass.

Application May 21, 1935, Serial No. 22,616

1 Claim. (Cl. 200—142)

This invention relates to electric fire alarms and has for an object to provide an extremely simple and durable circuit closer which will be positive in operation and will include an exposed 5 fusible strip and switch contacts connected to the strip and including a spring pressed movable contact which is adjustably connected to the strip and holds the strip under tension so that upon rupture of the strip due to fire in proximity to 10 the strip, the switch contacts will be sharply closed to close the alarm circuit.

A further object is to provide a circuit closer which may be easily applied to a horizontal or vertical support in the room or other locality to 15 be protected, and will include a movable rod carrying a switch contact in the nature of a cross arm which bridges fixed switch contacts arranged on either side of the rod in a casing or housing, and is held in tight engagement with the fixed 20 contact by a spring which encircles the rod and is held under tension between a nut on the rod and a transverse partition in the housing, the partition serving to separate the housing into two compartments one of which houses the switch 25 contacts only and the other of which houses the spring so that danger of a short circuit will be positively prevented.

With the above and other objects in view the invention consists of certain novel details of construction and combinations of parts hereinafter 30 fully described and claimed, it being understood that various modifications may be resorted to within the scope of the appended claim without departing from the spirit or sacrificing any of 35 the advantages of the invention.

In the accompanying drawing forming part of this specification,

Figure 1 is a front elevation of a fire alarm circuit closer constructed in accordance with my 40 invention.

Figure 2 is a longitudinal sectional view of the circuit closer.

Figure 3 is a detail cross sectional view taken on the line 3—3 of Figure 1.

45 Figure 4 is a diagrammatic view showing the circuit closer and circuit wires connecting the alarm devices thereto.

Referring now to the drawing in which like 50 characters of reference designate similar parts in the various views, 10 designates a cylindrical housing which may be attached to a vertical or horizontal support by means of screws 11. A circular cover 12 closes the front of the housing and is removably secured in position by means of 55 screws 13 passed through the cover and into lugs

14 carried by the cylindrical wall of the housing. A transverse partition 15 extends diametrically across the housing and divides the housing into two substantially equal compartments.

A rod 16 extends perpendicular to the partition 5 and is slidably mounted in the partition by means of a bushing 17. The rod projects outwardly through the cylindrical wall of the housing and is slidably fitted in said wall by means of a bushing 18. A helical spring 19 surrounds the 10 rod within the housing, one end of the spring bearing upon the bushing 17 and the opposite end bearing upon an adjusting nut 20 by means of which the tension of the spring may be regulated. A cross arm 21 is fixed to the rod on the 15 opposite side of the partition from the spring, by means of a set screw 22 and forms a movable switch contact.

A pair of fixed switch contacts 23 are secured to the rear wall of the casing by means of nuts 20 24 and are insulated from the wall by bushings 25. These contacts extend forwardly from the rear wall and are disposed in the path of movement of the contact 21. The free ends 26 of the fixed contacts are abruptly bent at a right angle 25 to the contacts as shown best in Figure 2 and form stops to prevent the contact 21 from displacement off the contacts 23 should the set screw 22 become loosened and permit the contact 21 to turn on the rod. Thus the positive operation 30 of the circuit closer is assured at all times.

A fusible strip 27 of celluloid or other material is provided at opposite ends with eyes 28 and 29 one of which is provided with a constricted neck 30 and beyond the neck terminates in a rounded head 31. An angle iron bracket 32 is provided in one arm with spaced fingers 33 between which the neck 30 is received, these fingers being bowed downwardly as shown best in Figure 2 and forming seats for the rounded head 31 of the eye 28. 40 The other leg of the bracket may be fastened securely to the support 34 to which the housing 10 is secured, a screw 35 or similar connector being passed through the leg and into the support as shown.

The other eye 29 of the fusible strip is provided with a yoke 36 having a transverse bridge 37 connecting the branches of the yoke and provided with an opening to receive a stud 38 formed integral with the head of an adjusting 50 screw 39, the stud being headed up as shown at 40 between the branches of the yoke to revolubly secure the adjusting screw to the eye 29.

The adjusting screw 39 is threaded into a socket 40 formed on the exposed end of the above 55

described rod 16. By turning the adjusting screw 39 the slack may be taken out of the fusible strip and further rotation of the screw will advance the rod 16 against the tension of the spring 19 and render the fusible strip taut.

The conductor wires 41 enter the casing 10 through an opening in the cylindrical wall thereof and are directed on opposite sides of the spring 19 and terminally connected to the fixed contacts 23 by nuts 42. It will be observed that the wires 41 and the spring 19 are housed on one side of the partition 15 while the switch contacts 21 and 23 are housed on the opposite side of the partition. Thus accidental short circuits are prevented since the switch contacts are confined in a separate compartment away from the metal spring or the wires 41.

By referring to Figure 4 it will be seen that the circuit closer is connected in series with a transformer 43, an audible alarm 44 and a visible alarm 45 as usual, so that upon a fire starting in the vicinity of the circuit closer the fusible strip will be ruptured and permit the circuit closer to close the circuit and energize the alarm devices.

From the above description it is thought that the construction and operation of my invention will be fully understood without further explanation.

What is claimed is:

In a fire alarm device, a cylindrical housing, a circular cover for the front of the housing, a partition extending diametrically across the housing, aligned insulating bushings in the partition and in the cylindrical wall of the housing, a rod slidably mounted in said bushings and extending exteriorly of the housing, a fusible strip adjustably secured to the rod outside of the housing and adapted to be anchored stationary at the free end, an expansion spring sleeved on the rod and bearing against the bushing in the partition for moving the rod endwise through the partition when the fusible strip melts, a transversely disposed switch contact adjustably mounted on the rod on the opposite side of the partition from the spring, a pair of switch contacts carried by the rear circular wall of the partition and insulated therefrom and having stops on the ends, said transverse switch contact being adapted to bring the fixed switch contacts and close an alarm circuit, and circuit wires entering the circular wall of the partition adjacent to said spring and passing through the partition, said circuit wires being terminally secured to respective ones of said fixed switch contacts.

EDWARD SARCIONE.
